UNITED STATES PATENT OFFICE.

HENRY S. GERMOND, JR., OF JERSEY CITY, NEW JERSEY, ASSIGNEE TO NEW YORK REVOLVING PORTABLE ELEVATOR COMPANY, OF JERSEY CITY, NEW JERSEY, A CORPORATION OF NEW JERSEY.

PORTABLE ELEVATOR.

1,130,080.

Specification of Letters Patent. Patented Mar. 2, 1915.

Application filed January 27, 1912. Serial No. 673,748.

To all whom it may concern:

Be it known that I, HENRY S. GERMOND, Jr., a citizen of the United States, residing at Jersey City, in the county of Hudson and State of New Jersey, have invented certain new and useful Improvements in Portable Elevators, of which the following is a specification, reference being had to the accompanying drawings.

10 This invention relates to improvements in elevators and particularly to improvements in elevators of the portable type; and an object of this invention is to provide an elevator of this type with means for increasing the stability thereof.

In the drawings illustrating the principle of this invention and the best mode now known to me of applying that principle, Figure 1 is a side elevation of so much of 20 a portable elevator as is necessary to illustrate this invention: Fig. 2 is a section on the line A—A of Fig. 1 and Fig. 3 is a view similar to Fig. 1 and shows my invention applied to a portable elevator of the non-25 rotatable type.

The truck-bed or carriage-body *a* is provided at its rear end with a pair of truck-wheels *b* and at its front end with a hanger or bracket *c* in which the steering-wheel *d* is pivotally mounted somewhat after the manner of a caster-wheel. Pivotally mounted upon the truck-bed *a* is the base *e* of the elevator frame. The load-carrying platform *f* is controlled by means of a windlass cable *h* which is wound upon a drum carried by the windlass shaft *m* and driven by a spur-gear *n*. The parts hereinbefore referred to are common to this type of elevator, one form of which is described in the 40 patent granted Thomas James McCarthy, May 28, 1907, No. 854,961.

The front of the truck-bed *a* is provided with a pair of brackets *f* in each of which is fulcrumed a bent lever or knee-lever *g*. The front ends of these knee-levers *g* are joined by a yoke *g'* formed integral therewith, while their rear ends form legs *h*. When the elevator is moved from place to place, it is supported upon the rear wheels *b* and steering wheel *d* and the yoke *g'* is raised (see dotted-line position of Fig. 1). However, when it is desired to load or unload the elevator, the yoke *g'* is thrown

downwardly into the position shown in Figs. 1 and 2 and the elevator-base is raised from 55 its normal running position. Hence, in this position of the legs *h* they support the weight at the front end of the elevator and, together with the wheels *b*, give to the elevator four points of support. In this position of the legs *h*, the steering wheel *d* is raised from the floor.

Referring to Fig. 3, the base of the elevator-frame is rigidly secured to the truck frame *a'*. The other parts are the same as 65 those pertaining to the construction illustrated in Figs. 1 and 2.

I claim:

1. The combination of a truck; a vertically-disposed guide-frame arranged thereon; a load-carrying platform movably mounted in said frame and projecting laterally therefrom; mechanism for controlling the position of said platform; and a pair of levers which are fulcrumed on said 75 truck adjacent to said guide-frame and the lower ends of which are arranged to be forced against the floor and thereby to raise the front part of the truck therefrom, whereby the weight resting upon the truck is supported upon the lower ends of said levers 80 and the rear wheels of the truck, and there is given said truck four points of support two of which are fixed.

2. The combination of a truck; a vertically-disposed guide-frame arranged thereon; a load-carrying platform movably mounted in said frame and projecting laterally therefrom; mechanism for controlling the position of said platform; a pair of 90 levers which are fulcrumed on said truck adjacent to said guide-frame and the lower ends of which are arranged to be forced against the floor and thereby to raise the front part of the truck therefrom, whereby 95 the weight resting upon the truck is supported upon the lower ends of said levers and the rear wheels of the truck, and there is given said truck four points of support two of which are fixed; and a yoke device 100 for connecting said levers, whereby the same may be operated practically simultaneously.

3. The combination of a truck having three wheels of which one is a steering-wheel; a vertically-disposed guide-frame ar- 105

ranged thereon; a load-carrying platform movably mounted in said frame and projecting laterally therefrom; mechanism for controlling the position of said platform; 5 and a pair of truck-raising members fulcrumed on said truck, one on each side of said steering-wheel, and arranged to be forced against the floor and thereby to raise the front part of the truck therefrom, where- 10 by the weight resting upon the truck is supported upon the lower ends of said members and the two wheels other than the steering-

wheel, and there is given said truck four points of support two of which are fixed.

In testimony whereof I hereunto set my 15 hand at the borough of Manhattan, city, county and State of New York, this eighteenth day of January, 1912, in the presence of the two undersigned witnesses.

HENRY S. GERMOND, JR.
